UNITED STATES PATENT OFFICE.

GEORGE H. ROSS, OF NEW YORK, N. Y.

WRINGER.

1,188,373.

Specification of Letters Patent. Patented June 20, 1916.

Application filed April 24, 1915, Serial No. 23,578. Renewed November 22, 1915. Serial No. 62,919.

To all whom it may concern:

Be it known that I, GEORGE H. Ross, a citizen of the United States, and a resident of the city of New York, borough of Brooklyn, in the county of Kings and State of New York, have invented a new and Improved Wringer, of which the following is a full, clear, and exact description.

This invention relates to machines for expressing water, juices or moisture of various kinds from cloths, clothing, fruit or other commodities, and has particular reference to a device providing for the thorough extraction of water or moisture from commodities by the application of a torsional force exerted through the rotation of a crank or its equivalent.

More definitely stated, among the objects of the invention is to provide a machine of the character indicated comprising a bag or receptacle of substantially cylindrical form and of a nature adapted to hold the commodity to be treated, means being provided to hold one end of the receptacle from rotation while the other end thereof is connected to a head caused to be rotated by means of a shaft to which power may be applied in any suitable manner, one of the ends or heads of the receptacle being adapted to slide toward or from the other to compensate for the torsional effect.

A further object of the invention is to provide adjustable means for supporting the receptacle in position for operation as over a tub, vat or other container.

The foregoing and many other objects of the invention will hereinafter be more fully described and claimed and illustrated in the drawings forming a part of this specification in which like characters of reference indicate corresponding parts in all the views, and in which—

Figure 1 is a side elevation of a preferred embodiment of the invention applied to a tub, one portion of the rear end of the device being in longitudinal section; Fig. 2 is a plan view; Fig. 3 is a vertical transverse section on the line 3—3 of Fig. 1; Fig. 4 is a front end elevation; Fig. 5 is a transverse section on the line 5—5 of Fig. 1; Figs. 6, 7 and 8 are detail sectional views on the corresponding lines of Fig. 4; and Fig. 9 is an inside elevation of the front head.

The several parts of this device may be made of any suitable materials, and the relative sizes and proportions, as well as the

general design of the mechanism, may be varied to a considerable extent without departing from the spirit of the invention hereinafter more fully described and claimed. I wish it to be understood also that while I may hereinafter refer to the function of the machine as that of wringing clothes over a tub, such description being adopted for convenience, the machine is adapted for many other analogous uses.

Referring more particularly to the drawings, I show at 10 a suitable receptacle or container adapted to sustain the machine in operation and which will be termed hereinafter for convenience a tub. At 11 is indicated the main frame element constituting a strut or bridge for the top of the tub and constituting the main support for the active portions of the device. At the front end of the strut is formed a vertical slot 12 adjacent which are upwardly projecting flanges 13, and at the extreme end of the strut are downwardly projecting lugs 14 through which binding screws 15 act against the outer wall of the front portion of the tub, while opposite the same are other lugs 14' coöperating with the inner wall of the tub. At the rear end of the strut is a vertical slot 16 bounded, as above described, at the sides by vertical parallel flanges 17, and below said flanges are arranged parallel shoulders 18 which, together with the slot, form a guideway extending longitudinally of the strut. The rear end of the strut is provided with a hole 19 in alinement with the longitudinal center of the guideway.

The numeral 20 indicates a front upright or standard pivoted at 21 in the front slot 12 and having a foot 22 bearing against the inner wall of the tub. The standard 20 has a cross pin 23 above the pivot 21 and adapted to bear against the upper edges of the flanges 13. The upper end of the standard 20 constitutes a tubular bearing 24 for a power shaft 25, the axis of which is maintained substantially parallel to the strut 11 and to the outer end of which is secured any suitable power device exemplified herein as a hand crank 26. A somewhat similar standard 27 is arranged at the rear end of the strut and is pivotally connected at 28 to a slide 29 movable in the guideway above referred to under the action of a screw 30 extending rearwardly through the hole 19 and having a winged nut 31 or its equivalent se-

2

cured thereto for drawing the slide and rear standard 27 rearwardly. This standard has a cross pin 32 bearing upon the upper edges of the flanges 17 and is provided at its upper 5 end with a tubular bearing 33 into which projects a tongue 34 rigidly secured to one side of the standard, as shown best in Fig. 3. When the parts are in normal operation, the axes of the bearings 24 and 33 coincide or 10 are in alignment with each other.

At 35 I show a front head secured in any suitable manner to the shaft 25 and of any suitable construction for the purpose of supporting one end of a reticulated member or 15 cage 36 of any suitable construction, depending upon the character of the service to be performed by the machine, but indicated herein as being composed of a circular series of twisted wire members 37 connected or 20 interlaced with which are circumferential members 38 of any suitable tough flexible nature. The head 35 is made in two parts, the part 35^a being arc-shaped and pivoted at 39 to the main head portion 35 so as to 25 swing outwardly around the pivot away from the axis of the shaft and bearing 24 leaving an opening in the cage 36 at one side. The ends of the wire or cables 37 are formed with ball-shaped heads 40 journaled 30 in correspondingly formed sockets 41 in the outer wall of the head 35 and held therein by means of a removable ring or plate 42 which, like the main head, is made in two parts for movement toward or from each other. Each 35 of the cables 37 is adapted to pass radially inwardly toward the center of the cage through a peripheral slot 43 terminating in a flaring enlargement 44 to allow free movement of such cable during the operation of 40 the device. At the other end of the machine is a rear head 45 having a swinging section 46 pivoted at 47 for relative movement similar to that already described in connection with the head 35 and the opposite ends of the 45 cables 37 have ball-shaped heads secured in the head 45 in the manner already described and locked therein removably by means of the plates 42. It will be seen, therefore, that it is feasible and sometimes desirable to 50 move the cage 36 so as to replace it with another cage of a different character, depending upon the service to be rendered. It is also to be observed that the cage already described may constitute a substantially permanent part of the machine, and in order to 55 avoid the necessity for frequent interchange of such parts, the cage described may constitute merely a support or reinforcement for a bag or auxiliary cage (not shown) 60 which may be carried therein and serving to hold the commodity to be acted upon.

The rear head is connected to a tubular shaft 48 supported in the bearing 33 and having oppositely arranged longitudinal 65 slots 49 into and through which said tongue

34 projects from the standard 27. A cap 50 or its equivalent closes the outer or rear end of the shaft 48. Between the cap 50 and the tongue 34 is a coil spring 51 which serves to hold or tend to hold the head 45 pressed rearwardly against the bearing 33 but adapted to yield to permit the shaft 48 and head to slide forwardly to compensate for the twisting or torsional effect of the cage 36 when the front head is rotated. It will be noted that the tongue 34 positively prevents rotation of the rear head and the rear end of the cage. 70 75

The arrangement of the heads 35 and 45 is such that the movable section of each opens outwardly from the main section in a direction to insure the automatic or practically automatic closing of the same when the shaft 25 is turned toward the right or in a clockwise direction as indicated in Fig. 4. In other words, as indicated by the diagonal dotted lines of Fig. 2, the rear movable section 46 opens downwardly toward the left of the operator while the movable section 35^a of the front head opens downwardly toward his right hand, and whether or not the cage is substantially closed by the operator before the wringing operation begins, the first effect of the turning of the shaft 25 will cause the main portion of the head 35 to move relatively toward the section 35^a causing such head to close, and such action through the cables connected to the portion of the head 35 on the other side of the shaft 25 from the pivot 39 will cause the section 46 of the rear head to move toward the non-rotary portion of the rear head, and the cage cannot open automatically or on account of the rotation of the shaft 25 whether locked closed or not. If desired, however, a hasp such as indicated at 52 connected to the main head member 35 may overlap the movable head member 35^a as shown in Figs. 4, 7 and 8, said hasp being provided with a hole or socket 52' into which a keeper 53 is adapted to snap. 90 95 100 105 110

As shown by the detail views in Figs. 6 and 7, the periphery of each head is arranged in the nature of a flange inclined inwardly with respect to the main portion of the head so as to bring any radial element of the flange perpendicular to a line leading therefrom to a point in the axis of the cage intermediate the heads. By this construction the draft of the cables 37 upon the peripheries of the heads will be borne approximately in perpendicular lines thereto. 115 120

With the parts arranged and supported as herein shown and described, the operation may be briefly summarized as follows: With the cage free and open and with the spaced edges thereof arranged, as indicated by the dotted lines *a* in Fig. 2, substantially parallel to the axis of the machine, the bag of clothes or other commodity to be treated may 125 130

be dropped within the cage and then the cage may be closed as already described and locked if desired. A rotation of the shaft 25 caused by the crank or otherwise in a clockwise direction will cause the front head to 5 rotate and the cage to twist as indicated in Fig. 1, and thereby apply sufficient pressure to the commodity to express the water or juices therefrom and without danger of 10 damaging the texture thereof in any manner. When sufficiently wrung which ordinarily may be accomplished by a very few turns of the crank, the front head will be returned to its original position and the cage will be 15 opened for the removal of the commodity.

I claim:

1. In a machine of the character set forth, the combination of front and rear heads arranged coaxially of each other, supporting 20 means for said heads, said supporting means serving to prevent rotation of one head, means to rotate the other head, and a reticulated cage connected to and extending between said heads, the heads each comprising 25 relatively movable parts adapted to open outwardly from the axis thereof to permit a commodity to be treated to be introduced into the cage.

2. In a machine of the character set forth, 30 the combination of a pair of disk-like heads having peripheral slots, means for supporting the heads in spaced relation coaxially of each other, means to hold one of the heads from rotation, means to rotate the other head around its axis, and a cage extending 35 between the heads and comprising a circular series of cables having their ends removably fitted in said peripheral slots.

3. In a device of the character set forth, 40 the combination of a pair of spaced parallel heads having alined axes, supporting means for the heads, one head support including means to prevent rotation of the same, means to rotate the other head around its axis, the 45 heads having an equal number of peripheral notches terminating at their inner ends in flared enlargements, and a cage supported upon said heads and extending between the same, said cage comprising a circular series 50 of cables having heads at their ends detachably connected to the heads through said notches and operating in said enlargements.

4. In a device of the character set forth, 55 the combination of a pair of spaced parallel disk-like heads arranged coaxially of each other, each head comprising an arc-shaped section movable with respect to the other member laterally from the axis of the head, each head having a series of peripheral 60 notches formed radially therein toward the axis terminating in ball-shaped sockets, the notched portion of each head constituting a flange inclined to the main portion of the head so as to be substantially perpendicular 65 to lines converging to a point in the axis

intermediate the heads, means to hold one of the heads from rotation, means to rotate the other head around its axis, and a cage extending between the heads and comprising a circular series of cables having ball-shaped 70 heads passed inwardly into said notches and into said sockets, and means coöperating with the outer surfaces of the heads to hold said cable heads in position.

5. In a wringer, the combination with a 75 pair of heads, a flexible reticulated cage supported upon and between said heads, and a pair of standards to support the heads, of supporting means for the standards comprising a strut arranged parallel to the axis 80 of the heads, said strut having a longitudinal slot adjacent each end, and means pivotally supporting said standards in said slots, substantially as set forth.

6. In a device of the character set forth, 85 the combination with a pair of heads, a flexible cage supported upon and extended between said heads, and a pair of standards supporting the heads coaxially of each other, of a rigid strut extending along the parts 90 aforesaid parallel to said axis, the strut having longitudinal slots adjacent its ends, one of the standards being mounted on a fixed pivot in one of said slots, a slide movable longitudinally of the strut along the other 95 slot, means pivoting the other standard to said slide, and means to control the position of the slide longitudinally of the strut.

7. In a wringer of the character set forth, 100 the combination with a pair of heads arranged in parallel spaced planes, a flexible cage supported upon and extending between said heads, and a pair of standards supporting the heads in axial alinement with each other, of a main frame member of rigid 105 material having adjacent each end a longitudinal slot and each slot being bounded on its sides with a pair of upstanding parallel flanges, means pivotally connecting said standards in said slots, and means carried by 110 the standards coöperating with the edges of said flanges to limit the movement of the standards away from each other.

8. In a wringer, the combination of front and rear heads arranged coaxially of each 115 other, a reticulated cage connected to and extending between said heads, the heads each comprising relatively movable parts adapted to open outwardly from the axis thereof to permit a commodity to be treated to be introduced into the cage, supporting means for 120 said heads, the supporting means for one head comprising a standard having a bearing, a tubular shaft mounted slidably in said bearing and having a slot formed therein, a 125 tongue carried by the standard and projecting through the slot into the shaft and serving to prevent rotation of the shaft but permitting the shaft and head connected thereto to slide toward the opposite head, and a 130

spring within the shaft bearing against said tongue at one end and serving to resist such sliding movement of the head, and means to rotate the opposite head in its supporting means.

9. In a wringer, the combination of front and rear heads arranged coaxially of each other, a reticulated cage connected to and extending between said heads, the cage having an open side and the heads comprising relatively movable parts permitting the heads to open outwardly from the axis thereof conjointly with the opening of the cage to permit a commodity to be introduced into or removed from the cage, means to rotate one of the heads, supporting means for the latter mentioned head permitting such rotation and preventing endwise movement thereof, and means supporting the other head preventing rotation thereof but permitting it to resiliently approach the rotating head, substantially as set forth.
10. In a wringer, the combination of a

pair of disk-like heads arranged coaxially of each other, a reticulated cage having its ends connected to the peripheries of the heads, the heads and cage being arranged to open outwardly with respect to the axis of the heads to permit a commodity to be introduced into or removed from the cage, means to rotate one of the heads, supporting means for this head serving to prevent endwise movement during its rotation, and supporting means for the opposite head including a tubular member having its axis coinciding with the axis of the cage and heads, and means coöperating with the tubular member serving to prevent rotation of the tubular member and head connected thereto but permitting such tubular member and head to resiliently move toward the rotary head.
